ABRADING TOOL

Ira J. Snader, Detroit, Mich., assignor to Ex-
Cell-O Corporation, Detroit, Mich., a corpora-
tion of Michigan

Application July 28, 1941, Serial No. 404,290

8 Claims. (Cl. 51—184.3)

The invention relates generally to abrading or lapping tools or the like for removing material by an abrading action from the surfaces of cylindrical bores.

More specifically, the invention is particularly applicable to an abrading tool which embodies a mandrel having tapering or wedge surfaces for effecting radial adjustment of abrading devices arranged to coact with said surfaces, and in which the abrading devices are arranged to present in any position of adjustment active abrading surfaces that are substantially segments of a cylinder and have flat supporting faces related to the axis of the cylindrical segments on an acute angle complementary to the angle of the tapering mandrel surfaces.

The primary object of the present invention is to provide a novel abrading tool of the foregoing character in which the abrading devices are positively connected with the mandrel by snugly interfitting parts effective to permit longitudinal adjustment along the tapering surfaces and at the same time to restrain the devices from leaving the surfaces in response to centrifugal force.

Other objects and advantages will become apparent from the following description and in the accompanying drawing, in which:

Figure 1 is an axial sectional view through an abrading tool embodying the features of the invention.

Figs. 2 and 3 are end and transverse sectional views of the tool respectively as indicated by the lines 2—2 and 3—3 of Fig. 1.

Fig. 4 is a perspective view looking toward the flat face of an abrasive element forming part of each device.

Fig. 5 is a perspective view looking toward the top of a holder forming part of each abrading device.

Fig. 6 is a perspective view looking toward the bottom of the holder.

Fig. 7 is a perspective view of the mandrel.

Fig. 8 is a view similar to Fig. 3, but of a modified form of tool.

Fig. 9 is a bottom view of the holder shown in Fig. 8.

Fig. 10 is a top view of the holder shown in Fig. 8.

Fig. 11 is a view similar to Fig. 3, but of still another modified form of tool.

While the invention is susceptible of various modifications and alternative constructions, I have shown in the drawing and will herein describe in detail the preferred embodiment, but it is to be understood that I do not thereby intend

to limit the invention to the specific form disclosed, but intend to cover all modifications and alternative constructions falling within the spirit and scope of the invention as expressed in the appended claims.

The abrading tool, which embodies the features of the present invention, comprises the mandrel 12 and the abrading devices 13 (two of which are herein shown) associated with the mandrel for quick assembly, accurate adjustment, and efficient operation.

The mandrel 12 in the preferred form shown in Figs. 1 and 7 is an elongated circular rod having a head 14 rigidly secured to its inner end. The outer end has oppositely disposed tapering wedge surfaces 15 which slope gently and uniformly to a relatively thin end 16 located on a diameter of the mandrel. An upstanding rib 17 extends longitudinally and substantially medially from the end edge of each tapering surface 15. The ribs on both surfaces are alike and are of uniform width and height. The ribs extend a substantial distance along the tapered surfaces, and beyond each rib and in longitudinal alignment therewith, the shank of the mandrel is grooved as at 18 approximately to the head 14. It will be understood that the mandrel 12 is adapted to be mounted in, and connected through the head 14 for rotary drive by, a supporting member, such as a tool spindle (not shown).

Each abrading device 13 includes an abrading element 19 (see Fig. 4) having an active face 20 of sectional cylindrical contour. Opposite the active face 20 is a flat face 21 defined preferably by the plane of a chord of the cylinder which is angularly related to the axis of the cylindrical surface at an acute angle complementary to the angle of a tapering mandrel surface 15. The resulting body of the abrading element 19 is somewhat shorter than the ribs 17 on the mandrel 12, and is shaped as a secantial segment of a cylinder tapering gradually and uniformly from end to end both in width and thickness. The active face 20 of the body is formed on a radius slightly greater than that of the mandrel. The width of the flat face 21 at the larger end is preferably only slightly less than the diameter of the cylinder. It is to be understood that the abrading element may be made of any suitable material, such for example as finely divided bonded abrasive.

The abrading element 19 is preferably mounted on a supporting member 22 constituting a holder or shoe to complete the abrading device 13. As illustrated in Figs. 5 and 6, one preferred form of holder 22 comprises a flat plate somewhat longer

than the abrading element 19 and shaped to taper uniformly from one end to the other in accordance with the taper of the flat face 21 of the abrading element. The varying width dimensions of the plate are slightly less than those of corresponding parts of the abrading element face 21 so that when the element and plate are appropriately secured together, as by adhesive, in face to face abutment with the wider dimensions substantially coinciding, the side margins of the abrading element will extend slightly beyond or overhang the margins of the plate (see Figs. 2 and 3). Thus, only the active face of the abrading element can ever contact the surface of the work.

The holder or plate 22 may be either a die casting or fashioned out of sheet metal, and is formed on the outer face 23 with suitable means for locating the abrading element 19 in proper registration. In one form, this means consists of two pins or lugs 24 projecting upwardly from opposite end portions of the plate 22 and extending into complementary holes or recesses 25 in the flat face 21 of the element 19. In a die casting, the pins 24 may be formed integral with the plate 22, and located on the longitudinal center line. The plate 22 is also formed in the inner face 26 with suitable means slidably interlocking with the rib 17 on the mating wedge surface 15 of the mandrel 12. To this end, the rib 17 is formed as a dovetailed guide, and the plate is formed with a longitudinal medial dovetailed guideway 27 slidably interfitting therewith. The relationship permits endwise movement of the abrading device 13 on the mandrel 12, but presents lateral separation in all positions of the adjustment and affords a positive rotary driving connection between the parts. The plane of the holder 22, when assembled with the abrading element 19, has the same angular relationship to the active cylindrical face 28 and to a tapering mandrel surface 15 as does the flat face 21 of the element. As may be seen in Figs. 2 and 3, the lateral dimension of the tapering mandrel surfaces 15 is narrower than the width of the flat faces 21 on the abrading elements 19.

A control and adjusting element is arranged to extend endwise from the narrower end of the plate 22 substantially as a continuation of the central section thereof. In this instance, the element consists of a thin elongated rod or wire 28 suitably secured at one end to the narrow end portion of the plate. The wire is dimensioned to seat relatively snugly in the related mandrel groove 18, and the free end thereof is bent to provide a right angular end portion 29 adapted to be anchored against endwise movement in the mandrel support.

In operation and assuming that the abrading devices 13 are assembled with the mandrel 12, and that the mandrel and the control elements 28 are connected to a suitable supporting and driving means, as shown for example in application Serial No. 264,706, filed March 29, 1939, by Paul R. Gjertsen, and issued as Patent No. 2,268,479 on Dec. 23, 1941, the abrading devices are adjusted to a minimum diameter or a sufficiently reduced diameter to enter the bore of the work to be lapped. The mandrel 12 is rotated, and, as the working operation continues, longitudinal adjustment of the mandrel relative to the control elements 28 is effected to increase the cutting diameter of the tool assembly progressively to the desired finished work size. During the rotation of the mandrel 12, either in or out of the work, the

abrading devices 13 are positively held against the wedge surfaces 15.

In the modified form illustrated in Figs. 8, 9 and 10, the holder 22^a consists of a sheet metal plate of which the medial longitudinal portion has been offset to one side to form a dovetailed guide groove 18^a adapted to interfit for relative longitudinal adjustment with the rib 17^a on one of the wedge surfaces 15^a of the mandrel 12^a. The offset portion defines a longitudinal medial upstanding rib or projection 30 on the opposed side of the holder 22^a. The abrading element 19^a is formed in the flat face 21^a with a longitudinal medial groove 31 of uniform width and height throughout its length and having parallel sides to receive the rib 30. Thus, the rib 30 and groove 31 serve the same function in this form as do the pins 24 and recesses 25 in the first form. In other respects the construction is similar to that shown in Figs. 1 to 7, and the corresponding parts are identified by the same reference numerals plus the latter "a".

In the second modified form of Fig. 10, the mandrel 12^b is formed along each wedge surface 15^b with a longitudinal medial rib 32 of T-shape in transverse form. The holder 22^b is formed in one side with a longitudinal medial T-slot 33 slidably engaging with the rib 32. In other respects the construction is similar to that shown in Figs. 1 to 7, and the corresponding parts are, therefore, identified by the reference numerals plus the letter "b".

It is to be noted that all three forms of the invention provide for interlocking slidable engagement between the mandrel and the holder to permit relative longitudinal adjustment while preventing transaxial separation, and provide means for locating the holder and the abrading element in predetermined relation. By reason of the foregoing construction, the tool is readily adjustable and at the same time the abrading elements are held against lateral separation regardless of whether the tool is in or out of the work. Consequently, the tool can be rotated at high speeds, and can be conveniently inserted into the work.

I claim as my invention:

1. A holder for the abrading element of an abrading tool comprising an elongated flat plate formed in one side with an intermediate longitudinally extending dovetail groove and provided on the other side with a plurality of longitudinally spaced upstanding projections adapted to interfit with the abrading element.
2. A holder for the abrading element of an abrading tool comprising a flat elongated plate formed in one side with a longitudinal medial groove having at least one undercut side and formed on the other side with two upstanding locating pins spaced longitudinally on the medial center line.
3. An abrading element for an abrading tool comprising a body shaped as a secantial segment of a cylinder, the plane of the secant cord being angular with respect to the axis of curvature of the cylindrical surface to provide a body of tapering width, the large end of said body being substantially flat, and the plane face of said body being formed with at least two longitudinally spaced recesses.
4. An abrading device for an abrading tool comprising, in combination, an elongated plate tapering in width from one end to the other end and having a longitudinal medial dovetail groove in one side, an abrading element having an elongated body shaped as a secantial segment of a

cylinder with the plane of the secant cord located at an acute angle to the axis of the cylindrical surface whereby the body has a gently tapering form, the flat face of said body being secured to the other side of said plate, and locating means interconnecting said plate and said element, said locating means consisting of two longitudinally spaced pins on said plate projecting into recesses in the flat face of said element.

5. A holder for the abrading element of an 10 abrading tool comprising an elongated flat plate formed in one side with an intermediate longitudinally extending T-slot constituting a groove with undercut sides and provided on the other side with a plurality of longitudinally spaced upstanding projections adapted to interfit with the abrading element.

6. An abrading device for an abrading tool comprising, in combination, an elongated flat plate formed in one side with an intermediate longitudinally extending dovetail groove and on the other side with a plurality of longitudinally spaced upstanding projections, and an abrading element having a body shaped as a secantial segment of a cylinder, the plane of the secant cord being angular with respect to the axis of curvature of the cylindrical surface to provide a body of tapering width, the large end of said body being substantially flat, and the plane face of said body being formed with a plurality of longitudinally spaced recesses interfitting with said projections to locate said element in definite rela-

tion to said plate, the longitudinal edges of said element extending beyond the corresponding margins of said plate.

7. An abrading element for an abrading tool 5 comprising a body shaped as a secantial segment of a cylinder, the plane of the secant cord being angular with respect to the axis of curvature of the cylindrical surface to provide a body of tapering width, the large end of said body being substantially flat, and the plane face of said body being formed with two longitudinally spaced holes located near opposite ends on the longitudinal medial center line of said face.

8. An abrading tool comprising, in combination, 15 a mandrel consisting of an elongated rod having a longitudinally inclined wedge surface formed with a longitudinally intermediate dovetail guide rib, a holder consisting of a flat plate having a dovetail groove in one side slidably engaging said rib and provided on the other side 20 with a plurality of longitudinally spaced upstanding projections, and an abrading element having an elongated body shaped as a secantial segment of a cylinder with the plane of the secant cord located at an acute angle to the axis of the cylindrical surface whereby the body has a gently tapering form, the flat face of said body being formed with a plurality of longitudinally spaced recesses interfitting with said projections to locate said element in definite relation to said plate.
